CLAIM

The ornamental design for a point-of-sale terminal, as shown and described.

DESCRIPTION

FIG. 1 is a front right perspective view of a point-of-sale terminal showing our new design;

FIG. 2 is a front view thereof;

FIG. 3 is a top view thereof;

FIG. 4 is a bottom view thereof;

FIG. 5 is a back view thereof;

FIG. 6 is a left-side view thereof;

FIG. 7 is a right-side view thereof; and,

FIG. 8 is a front left perspective view thereof.

The broken lines in the drawings depict portions of the point-of-sale terminal that form no part of the claimed design.

1 Claim, 7 Drawing Sheets
